(57) **CLAIM**

The ornamental design for a display panel of a digital camera with an icon, as shown and described.

DESCRIPTION

FIG. 1 is a front view of a display panel of a digital camera with an icon; and,

FIG. 2 is an enlarged front view thereof, the icon is shown separately for clarity of illustration.

The broken line drawing of a digital camera, words, letters, numbers and the graphical element are for illustrative purposes only and form no part of the claimed design.

1 Claim, 2 Drawing Sheets**FIG. 1**

FIG. 2
